APPARATUS FOR WASHING OVER, RELEASING, AND WITHDRAWING TUBULAR STRUCTURES FROM WELLS

Robbins M. Claypool, Bellaire, and David M. Best,
Houston, Tex.

Application March 6, 1947, Serial No. 732,860

18 Claims. (Cl. 166—1)

1

This invention relates to apparatus for performing the operations of washing over, releasing, and withdrawing from well bores that portion of pipe or tubing located at the bottom of the well bore, including or excluding any tool, packer, anchoring arrangement or other device which may have been installed with and as an integral part of said pipe or tubing, when said anchoring arrangement and/or lower portion of said tubing becomes stuck, fouled or otherwise cannot be pulled.

The primary object of the invention is to provide means of the character indicated in which all of the said operations are performed with means forming a part of and incorporated in the original setting hook-up assembly, thereby substantially eliminating the necessity for unscrewing, cutting in two, or otherwise releasing tubing string and removing same and then making various other trips into the well bore for the purpose of washing over, reversing, cutting and/or jarring in order to successively remove the balance of the tubing string, tool, packer, anchoring arrangement or other device.

A further object of the invention is to provide a means of the character indicated comprising a threaded screw-through joint, preferably including a rotary milling shoe, releasably joining a special section of externally and internally substantially flush wash pipe, with another special section of externally and internally substantially flush tubing including a special oppositely threaded release joint having a thread or spline identical with said sealed joint thread located on the outside upper portion thereof, said wash pipe and milling shoe being adapted to telescope over said tubing, and said release joint being located in said tubing string immediately above the tool, production packer, or other anchoring arrangement; and the novel subcombinations thereof.

Other and further objects of the invention will become apparent as the description proceeds, reference being made to the accompanying drawing forming a part of the disclosure, wherein:

Fig. 1 is a side elevation, partly in axial section of the upper portion of the tubing string of the present invention including the screw-through joint;

Fig. 2 is similar view of the lower portion of the tubing string including the release joint;

Fig. 3 is an enlarged fragmentary axial section of the screw-through joint; and

Fig. 4 is a fragmentary axial section of a modified form of screw-through joint, parts being shown somewhat exaggerated for clearness.

2

In the accompanying drawing, wherein for the purpose of illustration, are shown the preferred embodiments of our invention, and referring first to Figs. 1, 2 and 3, the numeral 1 designates the upper portion or wash pipe of the tubing string of the present invention. The wash pipe 1 may comprise one or more sections, and if more than one, the various sections are preferably connected together in such a manner as to render the pipe surfaces flush both externally and internally, although it is more important that this wash pipe be flush internally than externally due to a telescoping action to be later described.

The lower portion of the tubing string comprises the tubing or pipe 2 having a smaller outer diameter than the inner diameter of the pipe 1 to provide an annular passage for drilling mud or other fluid when the pipe 1 is telescoped over the pipe 2 in a manner to be later described.

The tubing 2 may also comprise one or more sections, and if more than one, the several sections are preferably connected together in such a manner as to render the pipe surfaces flush both externally and internally, although it is more important that the tubing be flush externally than internally due to the telescoping action previously noted.

The wash pipe 1 and the tubing 2 are releasably joined or connected together by means of a screw-through joint generally indicated by the numeral 3.

The screw-through joint 3 comprises a relatively short tubular member or section 4 having preferably the same outer diameter as the pipe 1, but a smaller inner diameter than the pipe 1, and hence the member 4 is of generally thicker construction than the pipe 1. The inner diameter of the member 4 is greater, however, than the outer diameter of the tubing 2, and the inner diameter 40 of the upper end portion 5 of the member 4 is gradually increased to equal the inner diameter of the pipe 1, and is provided with an outwardly offset internally threaded end 6 receiving the inwardly offset externally threaded lower end 7 45 of the pipe 1. The connection just described provides an internally and externally flush connection and similar connections may be used throughout in the pipe 1 if it is constructed of a plurality of sections. The member 4 is additionally provided internally with a screw thread 8, and the lower end thereof is provided with hard-faced cutting teeth 9. Thus the member 4, or the lower portion thereof may be considered a rotary milling shoe.

The screw-through joint 3 further comprises a relatively short tubular member or section 10

having preferably the same inner diameter as the tubing 2, but a larger outer diameter, and hence the member 10 is of generally thicker construction than the tubing 2. The outer diameter of the member 10 is less, however, than the inner diameter of the pipe 1, and the outer diameter of the lower end portion 11 thereof is gradually decreased to equal the outer diameter of the tubing 2, and is provided with an inwardly offset externally threaded end 12 received within the outwardly offset internally threaded upper end 13 of the tubing 2. The connection just described provides an internally and externally flush connection and similar connections may be used throughout the tubing 2 if constructed of a plurality of sections. The member 10 is additionally provided externally with a screw thread 14 receiving the screw thread 8 of the member 4.

The outer diameter of the member 10 is obviously substantially equal to the inner diameter of the member 4, and preferably, but not necessarily, this diameter is the median of the internal diameter of the pipe 1 and the external diameter of the tubing 2. Thus when the pipe 1 is telescoped over the tubing 2 in the manner to be later described, passageways of substantially equal area will be provided between the member 10 and pipe 1, and the member 4 and tubing 2, for the passage of drilling mud, etc.

To prevent "screwing through" of the screw-through joint 3, i. e., rotation of the member 4 relative to the member 10, until the actual need for it arises, a special plastic packing seal 15 is applied to the threads 8 and 14 just prior to assembly. A suitable plastic is diallyl phthalate prepolymer technical, a newly developed material brought out by Shell Development Corporation. The plastic packing seal 15, upon hardening or setting, renders the screw-through joint 3 sufficiently rigid or resistant to all of the torque necessary for the manipulation of the tubing during all setting operations.

A generally tubular release joint, generally indicated by the numeral 16, is connected to the lower end of the tubing 2. The internal diameter of the release joint 16 is preferably of the same inner diameter as the tubing 2 and also, the outer diameter of the upper end portion 17 and the lower end portion 18 is preferably the same as the outer diameter of the tubing 2.

The outer diameter of the upper intermediate portion 19 of the release joint 16 is increased and this portion of the joint is provided with a screw thread or spline 20 adapted to receive the thread 8 of the member 4 as indicated by the dot-dash lines in Fig. 2.

A radially outwardly extending annular shoulder or flange 21 is provided on the release joint 16 just below the lower end of the thread 20. The outer diameter of the shoulder 20 is preferably substantially equal to the outer diameter of the pipe 1 and the shoulder functions as a stop member limiting the downward movement of the pipe 1, member 4, etc., by engaging the teeth 9 of the member 4, thereby also stopping relative rotation between the pipe 1, member 4 and the tubing 2, and causing the tubing 2, member 10, and release joint 16 to rotate with the pipe 1 and member 4 when the latter are rotated.

The inner surface of the upper end 22 of the portion 17 of the release joint 16 is outwardly offset and provided with a screw thread receiving the inwardly offset outer surface threaded

lower end 23 of the tubing 2 thereby providing a flush connection as previously described.

Preferably all of the threads of the threaded connections above the flange 21 of the release joint 16 are right hand threads, as illustrated. This includes also any such connections as may be used in the string of manipulating tubing 24 connected in any suitable manner to the upper end of the pipe 1. Such threads, however, may be left hand threads, if desired, it being important only that they all be cut in the same direction.

The lower end portion 18 of the release joint 16 is externally threaded as indicated at 25, and the thread 25 is oppositely or reversely cut relative to the other threads in the assembly. Thus, as illustrated, the thread 25 is a left hand thread.

The thread 25 of the end portion 18 of the release joint 16 provides a connection for a tool, packer, anchoring arrangement, or other device, not illustrated.

The manipulative tubing 24 may have the same internal and external dimensions as the tubing 2, and the tubing 24 may be gripped in a rotary table in the conventional manner, which table may be actuated to rotate the entire tubing string, or a portion thereof, as will be later described.

With respect to the relative axial lengths of the wash pipe 1, and the tubing 2, the wash pipe 1 must be sufficiently longer than the tubing 2 that the teeth 9 of the member 4 will seat on or engage the shoulder 21. Examples of the relative lengths are 20 to 510 feet or over for the wash pipe 1, 10 to 500 feet or over for the tubing 2. These examples are given merely by way of illustration and not by way of limitation. In general, the wash pipe 1 will be from 5 to 10 feet longer than the tubing 2.

The modified form of screw-through joint 3' illustrated in Fig. 4 is substantially the same as the screw-through joint 3 except that the plastic packing seal 15 is replaced by a shear pin 26 suitably seated in a recess 27 provided in the external wall of the tubular member 10' and extending into an opening 28 provided in the tubular member 4'.

Preferably, the outer end portion of the opening 28 is threaded and the shear pin 26 is maintained in position by means of a set screw 29.

The shear pin 26 functions as does the plastic packing seal 15 to prevent "screwing through" of the screw-through joint 3', i. e., rotation of the member 4' relative to the member 10' on the threads 8' and 14', until the actual need for it arises. Thus the shear pin 26 renders the screw-through joint 3' sufficiently rigid or resistant to all of the torque necessary for the manipulation of the tubing during all setting operations.

To illustrate the operation of our structure, let it be assumed that the string comprises a production tubing string and that a conventional packer is connected to the thread 25 of the lower portion 18 of the release or safety joint 16. Then, when it becomes necessary to attempt removal of the production tubing string and packer, a pull on the tubing 24 from the top of the well is exerted and if the tubing and packer are free, they may be withdrawn from the well bore.

However, if permissible pulling indicates stuck or fouled condition of tubing and/or packer, drilling mud or other fluid pressure is applied to the string of tubing, the tubing 24 and wash pipe 1 are rotated to the right (for the directional cut of the threads illustrated) with approximately

500 lbs. weight down, thereby releasing the packing seal 15 or the shear pin 26, and the member 4 of the screw-through joint 3 screws through down over the tubing 2. Completion of the screwing through action is easily determined by weight equalization and circulation of drilling mud or other fluid being established through the tubing 24, the wash pipe 1, the annular passage between the wash pipe 1 and tubing 2, around the bottom end of the member 4 and upwardly around the exterior of the wash pipe 1 and tubing 24 to the top of the well.

The rotation and circulation is continued, the teeth 9 cutting away the material packed around the tubing 2, and the circulating drilling mud washing down over the flush joint tubing 2 and removing debris by means of the outer telescoping flush joint wash pipe 1, until by predetermined measurement the top of the packer is within a few feet, that is, above the portion 19 of the release joint 16 so that circulation of the drilling fluid may be continued. When this point is reached, rotation is stopped but circulation and washing down are continued until the packer top is reached.

Rotation is then continued until the screw thread 8 of the member 4 receives six or eight turns of the thread 20 of the release joint 16. This condition will be indicated by the stopping of the pumps circulating the drilling fluid due to the cutting-off of the circulation.

Next, another attempt to pull the entire string of tubing and packer is made, and if the packer is not vulcanized to the casing, the entire assembly can easily be pulled at this stage.

However, if the packer cannot be pulled, rotation of the tubing 24, wash pipe 1 and member 4 is continued, the teeth 9 engaging the shoulder 21 and causing the tubing 2 and release joint 16 to be turned therewith. Rotation of the release joint 16 causes the thread 25 thereof to be unscrewed from the packer, and then, all of the tubing may be withdrawn from the well bore.

The packer may then be removed by conventional fishing means.

It is possible that after screw through action is completed and washing down procedure is in progress a point might be reached in the downward telescoping travel of the washover pipe 1 over the lower tubing 2, due to dulling of milling shoe, collapse of outer casing or encounter with junk, beyond which downward travel can not be carried. When such a condition is encountered, the washover pipe 1 may be retracted until the screw through members 4 and 10 are slightly in contact, then, combining left hand rotation of the washover pipe 1 with a slight upward pull, the screw through joint 3 is unscrewed and the upper line of tubing 24 including the washover pipe 1 and the outer member or milling shoe 4 of the screw through joint may be withdrawn from the well bore. After this is done, the dull or worn milling shoe may be replaced with a new or sharp milling shoe and milling, washover action may be resumed and carried on to completion as previously described.

If for any reason downward progress of the washover pipe 1 is discontinued before completing full downward travel, and/or if for any reason connection can not be made with the release joint 16, an attempt to pull the entire string of tubing including the packer can still be made by simply retracting or pulling up the washover pipe 1 until the shoulders of screw through joint threads are in contact, and then the necessary

pull may be exerted to accomplish the desired result, i. e., removal of the tubing and packer.

It sometimes happens that only the packer is stuck in the well, in which event the screw thread 25 of the release joint will unscrew from the packer without breaking the seal 15 of the screw-through joint 3. Should this happen, the primary object of the invention will still have been accomplished since all tubing may then be easily withdrawn from the well bore.

As before, the packer may then be removed by conventional fishing means.

As stated previously, the structure herein disclosed is incorporated in the original production setting hook-up assembly, thus substantially eliminating the necessity for unscrewing, cutting in two, or otherwise releasing tubular string and removing same and then making various other trips into the well bore for the purpose of washing over, reversing, cutting and/or jarring in order to successively remove the balance of the tubing string and production packer. With the structure herein disclosed, only one fishing operation, at most, is required.

The initial cost of the structure herein disclosed, i. e., the flush joint tubing, the screw-through joint combined with a rotary milling shoe, and the release joint, is only slightly more expensive than the conventional type tubing, and when it is considered that the average fishing job which the present structure largely, if not completely, eliminates, may cost from 8 to more than 30 times the increase in initial cost of the assembly, the unexpected advantages of the present structure over the conventional type tubing are readily appreciated.

Although the disclosure herein is more or less specific to the use of the assembly in connection with production tubing and packer well settings, it is obvious that the same assembly is adapted to any number of other oil or water well operations such as, squeeze jobs, water well completions, dual completions, testing operations, etc.

In the above disclosure we have set forth two of the preferred embodiments of our invention, but it is to be understood that these are given by way of illustration, and not in limitation thereof.

We claim:

1. A string of tubing for use in wells comprising a wash pipe having a substantially flush inner surface, a line of tubing having a substantially flush outer surface, the inner diameter of said wash pipe being greater than the outer diameter of said line of tubing, said wash pipe being longer axially than said line of tubing, a screw-through joint connecting said wash pipe to said line of tubing, said screw-through joint comprising an outer, internally threaded tubular member connected to said wash pipe and an inner, externally threaded member connected to said line of tubing and in threaded engagement with said outer member, cutting teeth on the lower end of said outer member, a plastic packing seal releasably joining said outer and inner members, the outer diameter of said inner member and the inner diameter of said outer member being greater than the outer diameter of said line of tubing and less than the inner diameter of said wash pipe, and a tubular release joint connected to the lower end of said line of tubing, said release joint having an external thread adapted to receive the internal thread of said outer tubular member and a radially outwardly extending shoulder below said external thread, said release joint also having a lower threaded end, the di-

connected to the lower end of said line of tubing, said tubular joint having an external thread adapted to receive the internal thread of said outer tubular member.

14. In a string of tubing for use in wells, the combination comprising a wash pipe having a substantially flush inner surface, a line of tubing having a substantially flush outer surface, the inner diameter of said wash pipe being greater than the outer diameter of said line of tubing, said wash pipe being longer axially than said line of tubing, a screw-through joint connecting said wash pipe to said line of tubing, said screw-through joint comprising an outer, internally threaded tubular member connected to said wash pipe and an inner, externally threaded member connected to said line of tubing and in threaded engagement with said outer member, cutting teeth on the lower end of said outer member, and a plastic packing seal joining said outer and inner members, the outer diameter of said inner member and the inner diameter of said outer member being greater than the outer diameter of said line of tubing and less than the inner diameter of said wash pipe.

15. In a string of tubing for use in wells, the combination comprising a wash pipe having a substantially flush inner surface, a line of tubing having a substantially flush outer surface, the inner diameter of said wash pipe being greater than the outer diameter of said line of tubing, said wash pipe being longer axially than said line of tubing, a screw-through joint connecting said wash pipe to said line of tubing, said screw-through joint comprising an outer, internally threaded tubular member connected to said wash pipe and an inner, externally threaded member connected to said line of tubing and in threaded engagement with said outer member, cutting teeth on the lower end of said outer member, and a shear pin releasably joining said outer and inner members, the outer diameter of said inner member and the inner diameter of said outer member being greater than the outer diameter of said line of tubing and less than the inner diameter of said wash pipe.

16. In a string of tubing for use in wells, the combination comprising a wash pipe having a substantially flush inner surface, a line of tubing having a substantially flush outer surface, the inner diameter of said wash pipe being greater than the outer diameter of said line of tubing, said wash pipe being longer axially than said line of tubing, a screw-through joint connecting said wash pipe to said line of tubing, said screw-through joint comprising an outer, internally threaded tubular member connected to said wash

pipe and an inner, externally threaded member connected to said line of tubing and in threaded engagement with said outer member, cutting teeth on the lower end of said outer member, and means releasably joining said outer and inner members, the outer diameter of said inner member and the inner diameter of said outer member being greater than the outer diameter of said line of tubing and less than the inner diameter of said wash pipe.

17. In a string of tubing for use in wells, the combination comprising a wash pipe, a line of tubing, the inner diameter of said wash pipe being greater than the outer diameter of said line of tubing, a screw-through joint connecting said wash pipe to said line of tubing, said screw-through joint comprising an outer, internally threaded tubular member connected to said wash pipe and an inner, externally threaded member connected to said line of tubing and in threaded engagement with said outer member, cutting teeth on the lower end of said outer member, and means releasably joining said outer and inner members, the outer diameter of said inner member and the inner diameter of said outer member being greater than the outer diameter of said line of tubing and less than the inner diameter of said wash pipe.

18. In a string of tubing for use in wells, the combination comprising a wash pipe, a line of tubing, the inner diameter of said wash pipe being greater than the outer diameter of said line of tubing, a screw-through joint connecting said wash pipe to said line of tubing, said screw-through joint comprising an outer, internally threaded tubular member connected to said wash pipe and an inner, externally threaded member connected to said line of tubing and in threaded engagement with said outer member, cutting teeth on the lower end of said outer member, and means releasably joining said outer and inner members, the outer diameter of said inner member and the inner diameter of said outer member being greater than the outer diameter of said line of tubing and less than the inner diameter of said wash pipe.
